UNITED STATES PATENT OFFICE.

JOHN J. KEYES, OF WILKINSBURG, PENNSYLVANIA, ASSIGNOR TO WESTINGHOUSE ELECTRIC & MANUFACTURING COMPANY, A CORPORATION OF PENNSYLVANIA.

METHOD OF MAKING INSULATING MATERIAL.

Application filed August 8, 1919. Serial No. 316,104.

To all whom it may concern:

Be it known that I, JOHN J. KEYES, a citizen of the United States, and a resident of Wilkinsburg, in the county of Allegheny and State of Pennsylvania, have invented a new and useful Improvement in Methods of Making Insulating Material, of which the following is a specification.

My invention relates to attachments for presses and it has, for its primary object, the provision of attachments for presses which shall permit of pressing fibrous material, impregnated with a suitable binder, in such form as to make the material suitable for utilization in separating the coils of shell-type transformers or for other purposes of manufacture in which a corrugated strip of insulating material is of value.

In the manufacture of shell-type transformers, the flat windings are supported in spaced relation by employing a curved strip of insulating material. The insulating material employed, heretofore, has been fuller-board, or a material of a similar nature, cut into strips by a bandsaw which necessitates cutting the strips in a serpentine or corrugated form. The curved strips are especially adapted for separating the various coils of the transformer as they provide a better mechanical structure than straight strips. Although strips of this character are especially suitable for the work, they are more or less difficult to form, as it requires careful work in cutting the strips into the proper shape.

One object of my invention resides, therefore, in the provision of apparatus which shall facilitate forming insulating material of suitable shape for employment in the manufacture of shell-type transformers.

Another object of my invention is to set forth a suitable material which is especially adapted for insulating purposes and which possesses a high mechanical strength and also lends itself readily to being formed into the proper shape by the apparatus provided by my invention.

With these and other objects in view, my invention will be more fully described, illustrated in the drawings, in the several views of which corresponding numerals indicate like parts, and then particularly pointed out in the claims.

In the drawings, Fig. 1 is a side elevation,

parts being broken away, of attachments for a press provided by my invention; Fig. 2 is a similar view of attachments for a press illustrating a modification of my invention; Fig. 3 is a side view of press attachments illustrating another modified form of my invention; Fig. 4 is a view of a curved strip of insulating material constructed in accordance with my invention, and Fig. 5 is a sectional view taken substantially along the line V—V of Fig. 4.

In practising my invention, I may employ an ordinary press, utilized in compacting various materials and I may provide this press with attachments or platens which may be employed to compact fibrous material in such manner that strips of it may be easily cut to provide a corrugated or curved strip of insulating material. The platens may have grooved surfaces, between which layers of the fibrous material impregnated with a suitable binder may be compacted in corrugated form. The platens may also be provided with means for so heating them that the fibrous material may be compacted and the binder hardened in one operation. Although my invention contemplates the construction of insulating material suitable for employment in the manufacture of shell-type transformers, insulating material may be provided in a like manner which may be utilized in various structures other than transformers.

In Fig. 1 is shown a plurality of press platens 1 and 2, the press platen 1 being connected to a press ram 3. Each of the platens may be formed with a grooved working face, as indicated at 4. The grooved working faces, of the platens 1 and 2, when in engagement, fit together and cooperate to press sheet material 5, disposed between them into a curved or corrugated sheet. The lower or movable platen 1 may be provided with suitable openings 6 through which a heating fluid may be forced to supply heat when fibrous material, impregnated with a binder adapted to harden under the application of heat, is being pressed. However, either of the platens, or both, may be provided with suitable heating means, if desired. The upper platen 2 may be secured to a supporting plate 7 by links 8 carried by pins 9 secured to the ends of the supporting plate 7 and the platen 2. The ends of the

supporting member 7 and the platen 2 may be held in spaced relation by a helical spring 10 having its ends disposed in suitable recesses provided in the respective ends of the 5 two members.

The links, above mentioned, are preferably of different lengths so that the upper platen 2 first engages the lower platen 1 at one end and engages it successively as the 10 lower platen is moved up into position. The successive engagement, of the grooved surfaces in this manner, insures proper pressure application upon the fibrous material and obviates any danger of the fibrous material being torn as it is forced into the 15 grooves. The spring 10 may be omitted if desired, but this spring insures such engagement at one end of the sheet that it will be drawn into the grooves from the 20 other side of the platens as their working surfaces progressively engage. The links, which support the upper press platen, being of different lengths, permit of an initial engagement of the press platens at one side 25 and also permit of a subsequent progressive engagement as the lower press platen is moved up into position.

In Fig. 2 is shown a modification of my invention in which the upper press platen 30 2 is formed of separable sections 11 which may move relative to each other. On account of the upper press platen 2 being formed of a plurality of sections, a slightly modified form of support must be provided 35 therefor. I have shown, therefore, a plate 12 which may be secured to the supporting member 7 and may be provided with slots 13 adapted to receive pins 14 which are secured to the sections 11. A pressure member 15 may be disposed between the separable sections 11 and the supporting member 7 and upon one end of which the spring 10 may be supported in a manner similar to that shown in Fig. 1. The slots 13 may be 40 of different lengths, the longest slot being, preferably, near the end of the plate adjacent the spring 10. The section 11, being so supported, will, therefore, successively engage the working face of the lower platen 1 as it is advanced upward into position. The separable sections 11 are, of course, formed with faces adapted to fit snugly into the grooved face of the lower platen 1. By 45 supporting the sections 11 by means of pins 50 carried in slots provided in the plate 12, relative movement of them is permitted and they are also so held together that they will always properly engage the working face of the lower platen.

The operation of the attachment above described is exactly similar to the attachment shown in Fig. 1. As the lower press platen is advanced, upon which the material to be pressed is placed, the separable sections 55 engage one end first and successively

engage it as the lower press platen is moved upward. The sheet of material will, therefore, be drawn into the grooves from one side and will be thoroughly compacted when all of the sections have moved into position 70 and sufficient pressure has been applied.

In Fig. 3 is shown another modified form of my invention in which the separable sections 11 are supported by the pins 14 disposed in the slots 13 provided in the plate 75 12, but, in this instance, the slots 13 are all of equal length. In order to procure successive engagement of the sections with the lower platen and to insure the sheet material being drawn smoothly into the 80 grooves, the central section is forced to first engage the material, by employing a member 16 pivoted at its central portion, as indicated at 17, and disposing it between the separable sections 11 and the supporting member 85 7. The spring 10, in this instance, is disposed with one of its ends engaging the pivoted central portion of the member 16 and its other end is disposed in a suitable recess 18 in the supporting member 7.

In operation, the above described modification of my invention is substantially the same as the attachments described heretofore. In this instance, however, the central section makes the initial engagement and, as the lower press platen is pressed upward, the sections on either side of it successively engage the sheet material disposed upon the lower press platen. The material is drawn in from each side, and, after the sections are all in correct position, the sheet material is thoroughly compacted by the 100 application of sufficient pressure.

I have found that a suitable material, which may be employed in constructing a 105 curved or corrugated strip by utilizing the above described apparatus, may comprise sheets of fibrous material impregnated with any suitable binder such, for example, as a phenolic condensation product. A number of sheets may be impregnated with a binder and stacked to a suitable thickness. The stacked material may then be disposed upon the lower platen of the press and the pressure applied by forcing it into engagement with the upper platen. If a phenolic condensation product is employed as a 110 binder, heat may be applied, together with the pressure, to harden the binder to its substantially insoluble and infusible state. Large sheets of such material may be compacted and the sheets may then be cut to 115 form strips of suitable thickness. A strip of insulating material may be provided, such as shown in Fig. 4. The width of the 120 cut strip will, of course, be the thickness of the sheet material and the thickness of the strip will depend upon the manner of cutting.

The method of forming insulating strips, 125

above described, facilitates and promotes rapid production of such strips on account of the fact that they may be cut from a corrugated sheet and may, therefore, be cut straight, the proper curved shape being provided by the corrugations. It will be appreciated, of course, that various materials may be employed in forming the insulating strips. I have mentioned fibrous material and a phenolic condensation product as these are well suited for forming strips of insulating material possessing great mechanical strength and high insulating qualities.

Although I have specifically described a plurality of attachments which may be employed in presses to form insulating strips which may be utilized in transformer manufacture, it will be apparent that minor changes may be made in the attachments and various other applications found for the material without departing from the spirit of my invention, and I desire, therefore, that no limitations shall be imposed

except such as are indicated in the appended 25 claims.

I claim as my invention:

1. A method of making insulating material that comprises impregnating sheet material with a binder, stacking the sheets 30 to form a body of suitable thickness, applying pressure upon the material to progressively form corrugations and compact the material, applying heat to first soften and then harden the binder and cutting material into strips of suitable thickness.

2. A method of making insulating material that comprises impregnating sheet material with a binder, stacking the sheets to form a body of suitable thickness, applying pressure upon the material to progressively form corrugations and compact the material, and applying heat to first soften and then harden the binder.

In testimony whereof, I have hereunto 45 subscribed my name this 30th day of July 1919.

JOHN J. KEYES.
